United States Patent Office

Des. 185,939
Patented Aug. 18, 1959

185,939

MOBILE KITCHEN AND SERVING UNIT

William H. Frick, Cleveland, Ohio

Application October 11, 1957, Serial No. 48,064

Term of patent 14 years

(Cl. D81—10)

Fig. 1

Fig. 3

Fig. 1 is a front perspective view of a mobile kitchen and serving unit, embodying my new design;

Fig. 2 is a rear view; and

Fig. 3 is an end view.

I claim:

The ornamental design for a mobile kitchen and serving unit, as shown.
